UNITED STATES PATENT OFFICE.

CHARLES EDWARD HAVILAND, OF LIMOGES, FRANCE.

DESIGN FOR A COVERED DISH OR SIMILAR ARTICLE.

SPECIFICATION forming part of Design No. 32,873, dated June 26, 1900.

Application filed May 31, 1900. Serial No. 18,683. Term of patent 7 years.

To all whom it may concern:

Be it known that I, CHARLES EDWARD HAVILAND, a citizen of the United States, residing at Limoges, in the Republic of France, have 5 invented and produced a new and original Design for a Covered Dish or Similar Article, of which the following is a specification, reference being had to the accompanying drawings, forming a part thereof, and in which—

10 Figure 1 is a side elevation of a covered dish bearing and incorporating my design. Fig. 2 is a top view of same, and Fig. 3 is a horizontal section of a portion of same on the dotted line 3 3 of Fig. 1.

15 The leading features of my design consist of the ornamental form and configuration of the dish and its cover, substantially as illustrated in the drawings.

In the drawings, A designates the body of 20 the dish, and B the cover therefor. The body

A has the downwardly-extending side surfaces C and the thence inwardly and downwardly extending surfaces D, which terminate at the ornate scalloped base E. The body A bears along its upper edge the scalloped ornate configuration F, and at its ends has handles G. The cover B has an elevated central portion bearing the handle H, and the edges of said cover are scalloped, as at I, to harmonize with the scalloped configuration 30 F along the upper edges of the body A. 25

What I claim is—

The design for a covered dish or similar article, substantially as shown and described.

Signed at Paris, in the Republic of France, 35 this 17th day of May, A. D. 1900.

CHARLES EDWARD HAVILAND.
